UNITED STATES PATENT OFFICE.

ORREN D. PURINGTON, OF PROVIDENCE, RHODE ISLAND.

CONCRETE FLOOR CONSTRUCTION.

Application filed February 9, 1922. Serial No. 535,170.

To all whom it may concern:

Be it known that I, ORREN D. PURINGTON, a citizen of the United States, residing at Providence, in the county of Providence and State of Rhode Island, have invented new and useful Improvements in Concrete Floor Constructions, of which the following is a specification.

This invention relates to certain new and useful improvements in concrete floor constructions, and pertains more especially to an improved means and method of constructing the floor.

The primary object of the invention is to provide improved means for enabling the floor to be easily and quickly constructed and for allowing the form, after setting of the concrete, to be easily and quickly collapsed and removed, thus providing for expeditious formation of the floor.

A further object of the invention is to provide a form or false structure which is simple and economical and which at the same time is effective for the purpose, holding the concrete firmly in position until setting or hardening thereof.

With further and other objects later to be set forth and manifested in the course of the following description, the invention relates in the construction and combination of the various parts now to be described and later claimed.

In the drawings:

Figure 1 is a vertical sectional view taken through one of the I-beams;

Figure 2 is a top plan view of one of the form clamps;

Figure 3 an inner end elevation of Figure 2; and

Figure 4 is an outer end elevation of Figure 2.

In proceeding in accordance with the present invention, a series of I-beams 1, are employed and laid in the desired spaced location, but one beam being shown in the drawings.

Each beam has its base engaged by the nose or upper jaw 2 of a clamp 3 and by a lower L-shaped jaw 4 formed on a central web 5 carried by the clamp. The jaws 2 extend outwardly from the vertical bodies of the clamps which latter are relatively wide or of plate-like form, while the webs 5 are at right angles to the clamp bodies. The clamps are formed with lateral arms or ledges 6 having upwardly extending flanges

7 and further have depending extensions 8 that have spaced upper and lower flanges 9 and 10 to receive a connecting bar 11 which latter is slotted at its ends at 12 to receive bolts 13 which latter clamp the bar 11 adjustably to the clamps thereby to secure the latter firmly and rigidly to the beam bases. The flanges 9 and 10 prevent all rocking or pivotal movement of the clamps about the bar 11 and consequently the parts are rigidly related and held against all movement.

In operation, the clamps are first engaged with the opposite sides of the beam bases and the bars then applied and properly adjusted and the bolts 13 then tightened. A false flooring 14 is now supported on the connecting bars 11 beneath the beam base so that it will be seen that the bars 11 thus function in a dual manner. Timbers 15 are now set or laid on edge on the arms or ledges 6 and are engaged with the flanges 7 so that the latter function to hold the timbers against outward movement. Boards 16 are now laid against the timbers 15, a rough flooring 18 being supported on tops of the cross timbers 17. The parts now occupy the position of Figure 1 whereupon grout or concrete is poured into the mold formed as shown and is tamped and leveled to about the line C indicated in Figure 1 of the drawings. Upon setting of the concrete, the form or false structure is collapsed which is attained by removing or knocking out the timbers 15, when the entire false structure will practically collapse, the bars 11 being then removed permitting the flooring 14 to drop down. The clamps may be easily removed by tapping same with a hammer, following which the spaces left in the concrete by the clamps may be filled or pointed up with concrete.

From the foregoing it will be seen that the entire beam is embedded in the concrete and the clamps with the connecting bar thereof, support the entire false frame structure.

Having thus described my invention, what I claim as new and desire to secure by Letters Patent is:-

1. In concrete floor construction, in combination with I-beams, clamps having upper and lower jaws engaged with the bases of the beams and having depending parts formed with spaced horizontal flanges, a connecting bar for the clamps engaged at its ends with the flanges, means to adjustably

secure the bar ends to the clamps, a false flooring seated on top of the bar, said clamps having lateral arms flanged at their outer ends, timbers supported on the arms and engaged with the flanges, boards engaged with the inner sides of the timbers, cross timbers seated on the first named timbers, and flooring seated on the cross timbers.

2. In concrete floor construction, in combination with I-beams, clamps engaged at their upper ends with opposite sides of the base of the beams, a connecting bar for the lower ends of the clamps disposed below the beams, flooring supported on the bar, lateral arms carried by the clamps, side boards supported by the arms, and top boards supported above the side boards.

3. In concrete floor construction, in combination with a beam, clamps having vertical plate-like bodies with elongated horizontal upper jaws to engage the upper sides of the beam base and central webs at right angles to the plane of the bodies and formed with lower jaws at their upper ends to engage the lower sides of the beam base, connecting means for the clamps secured to the webs, and forms carried by the clamps.

4. In concrete floor construction, in combination with a beam, clamps having upper jaws and central webs formed with lower jaws to receive the sides of the beam base, extensions depending from the webs and formed with spaced horizontal flanges, a connecting bar for the clamps engaged with and in the space between the flanges, flooring supported on the bar, lateral arms on the clamps, and side and top boards supported by the arms.

5. In concrete floor construction, in combination with a beam, clamps having elongated horizontal upper jaws to engage the upper sides of the beam base and central webs formed with lower jaws at their upper ends to engage the lower sides of the beam base, spaced upper and lower abutments on the webs, a connecting bar for the clamps engaged in the spaces between and with the abutments, means to secure the bar to the webs and forms carried by the clamps.

50 6. In concrete floor construction, in combination with a beam, clamps having relatively wide bodies and webs abutting the bodies and disposed in a plane at right angles to the plane of the bodies, the bodies being formed with lateral upper jaws engaging the upper sides of the beam base and the webs having cutouts in the front edges of the webs below and adjacent to the upper

jaws to form lower jaws which receive the outer longitudinal edges of the beam base and engage the lower sides of the beam base, connecting means for the clamps, and forms carried by the clamps.

7. In concrete floor construction, in combination with a beam, clamps having vertical parts provided with spaced upper and lower jaws receiving and engaging the sides of the beam base, laterally extending parts carried by the vertical parts of the clamps and disposed below the beam base, connecting means for the clamps and forms supported on the laterally extending parts and against the vertical parts.

8. In concrete floor construction, in combination with a beam, clamps depending from the beam and having their upper ends formed with spaced upper and lower jaws engaging opposite sides of the beam base, connecting means for the lower ends of the clamps disposed below the base of the beam, means to secure the connecting means to the clamps so as to prevent relative pivotal movement of the parts, and forms carried by the clamps.

9. In concrete floor construction, a beam, clamps having spaced upper and lower jaws engaged with opposite sides of the beam and depending therefrom, forms on opposite sides of the beam, means to support the forms from the respective clamps, connecting means for the clamps extending in spaced relation to the beam base and below and across the latter, floor boards supported on the connecting means, and removable means to independently secure the ends of the connecting means to the respective clamps whereby upon removal of the securing means the connecting means may be removed.

10. In concrete floor construction, in combination with a beam, substantially vertical members having parts at their upper ends engaged with the opposite sides of the base of the beam, lateral supports carried by the members and located below the beam base, forms supported on the lateral supports and against the members, and connecting means for the vertical members disposed below the lateral supports.

In testimony whereof I have signed my name to this specification in the presence of a subscribing witness.

ORREN D. PURINGTON.
